DESIGN FOR A LIPSTICK CONTAINER

Robert T. Christy, New York, N. Y., assignor to William E. Vogelback, Chicago, Ill.

Application May 29, 1940, Serial No. 92,689

Term of patent 3½ years

To all whom it may concern:

Be it known that I, Robert T. Christy, a citizen of the United States of America and resident of the city, county, and State of New York, have invented a new, original, and ornamental Design for a Lipstick Container, of which the following is a specification, reference being had to the accompanying drawing, forming part thereof.

In the drawing:

I claim:

The ornamental design for a lipstick container, substantially as shown.

ROBERT T. CHRISTY.
